Patented May 18, 1915.

UNITED STATES PATENT OFFICE.

JOHN N. REYNOLDS, OF GREENWICH, CONNECTICUT, ASSIGNOR TO WESTERN ELECTRIC COMPANY, OF NEW YORK, N. Y., A CORPORATION OF ILLINOIS

SELECTOR-SWITCH.

1,139,722.

Specification of Letters Patent.

Patented May 18, 1915.

Application filed May 10, 1913, Serial No. 766,880. Renewed March 25, 1915. Serial No. 17,052.

To all whom it may concern:

Be it known that I, JOHN N. REYNOLDS, a citizen of the United States, residing at Greenwich, in the county of Fairfield and State of Connecticut, have invented a certain new and useful Improvement in Selector-Switches, of which the following is a full, clear, concise, and exact description.

This invention relates to improvements in telephone switch mechanisms such as shown in my copending application Serial No. 766,879, filed May 10, 1913, and is particularly designed for use as a line switch or trunk finder, although obviously it is adapted to be used for other purposes.

The principal object of this invention is to provide a switch of this character in which the terminal contacts are mounted in a bank and in which the connection between incoming and outgoing line terminals is effected by the successive rotary movement of a pair of bars or shafts.

Other objects and advantages will appear as the description of the invention progresses.

In order to facilitate the explanation and understanding of this invention, it will now be described as a line switch or trunk finder and as such might be arranged to serve, for example, a group of one hundred subscribers' lines and a corresponding group of trunk lines. It is of course obvious that in the following description, the terms "incoming lines" and "outgoing lines" might be substituted for lines or subscribers' lines and trunk lines respectively.

The embodiment of the apparatus herein disclosed comprises two sets of substantially parallel rotatable bars or shafts corresponding to the subscribers' lines and trunk lines respectively. These bars at each of their adjacent points or points of intersection are provided with contact operating means, each trunk bar being provided with a rotatable and flexible arm and each line bar with a cam. Line terminals and trunk terminals in the form of projecting contact springs are rigidly mounted in a frame or terminal bank at one side of and parallel to the bars with their free ends projecting outwardly in a position to be actuated by the contact operating means of a pair of bars upon the successive rotary movement of a bar of each set. One of the trunk bars or

shafts would normally be displaced to a position such that the succeeding rotary movement of a line bar would effect interengagement of the terminals of the line with the terminals of the trunk corresponding to the preselected or "set" trunk bar.

For a more complete disclosure, reference is now made to the drawing which shows a perspective view of the device with parts broken away and in which,

1 represents a base or supporting member of any desired kind. Mounted upon the base 1 at the rear thereof is a terminal bank 2. Projecting upwardly from said base at each end thereof are the supporting bars 3 and 4 respectively. Pivotedly mounted in the supports 3 and 4 is a plurality of rotatable bars or shafts 5 hereinafter to be referred to as line bars. One of these bars will be provided for each incoming line to be served. Pivotedly mounted between the base member 1 and the supporting brackets 6, projecting from the upper portion of the terminal bank 2, is a plurality of trunk bars 7, one for each trunk, or out-going line. The bars of these two sets are in parallel planes and adjacent to each other and, at each of the points where the bars cross or intersect, that is at the points where they are adjacent to one another, they are provided with coöperating contact actuating means hereinafter to be described. Projecting outwardly from the terminal bank with their free ends in proximity to the adjacent points of said bars is a plurality of contact sets. Each set, as illustrated, consists of line terminals 8, 9 and 10 and trunk terminals 11, 12 and 13. All the corresponding line terminals which project outwardly in a position to be actuated by the same line bar 5, are multiply connected by being formed as integral portions of conducting strips 14, 15 and 16 respectively, and all the corresponding trunk terminals of the sets which extend in a position to be actuated by the same trunk bar are multiply connected by the conductors 17, 18 and 19 respectively. Mounted between the springs 8 and 12 and 9 and 13 respectively are the insulating spacing blocks 41 and 42.

Rotatably mounted on each of the trunk bars 7 by means of the yokes 20 is a plurality of contact actuating arms 21, one being provided for each line bar and in a plane slightly above it. Each of these arms

is provided at the outer end thereof with an insulating knob 40 which, upon anti-clockwise rotary movement of its supporting bar 7, is adapted to be positioned immediately under the lowermost spring 10 of its respective contact set. These arm 21 are so formed that they may be readily flexed in the plane of their supporting shafts but are comparatively rigid in a direction transverse thereto. Rigidly secured to the shaft 7 between the upper and lower members of the yoke is a sleeve 22 which prevents longitudinal movement of the arm on the shaft. Encircling the sleeve, with one end secured thereto and the other end to the yoke, is a spring 23 which serves when the bar is in normal position to retain the contact actuating arms in a position slightly to the right of the coöperating contact operating member on the corresponding line bar.

Rigidly secured to the line bars, adjacent to and preferably under the free ends of the contact sets respectively, is a plurality of grooved cam members 24, one being provided for each contact actuating arm 21 which is adjacent thereto. Rigidly secured near the lower end of each of the trunk bars 7 is an armature 25 normally held retracted against the stop pin 26 by the spring 27.

Mounted in operative relation to each armature 25 is an electromagnet 28 adapted to rotate said bar in anti-clockwise direction as viewed from above. Rigidly secured to each line bar 5 and projecting downwardly therefrom is an armature 29 normally held retracted against the stop 30 by the spring 31. Mounted in operative relation to each armature 29 is an electromagnet 32 so located that upon energization it will rotate said bar in a clockwise direction as viewed from the right.

33 and 34 represent any appropriate circuit controlling devices which are adapted at appropriate intervals to close an energizing circuit for the electromagnets 28 and 32 respectively.

Having now described the structure of the switch, its operation briefly will be as follows: Through the operation of circuit controlling means, which need not be here described, some one of the electromagnets 28 will at all times be energized and consequently one of the trunk bars 7 will at all times be rotated to set or operative position. This rotation of the trunk bar will place each of its insulating portions 40 in operative relation, or, as shown in the drawings, directly under its respective contact set and directly over its coöperating cam on the line bar. Now upon the event of an incoming call, one of the electromagnets 32 will become energized through the operation of the appropriate circuit controlling devices, thus rotating the corresponding line bar 5. The grooved cam 24 will thus engage the

insulating knob 40, flexing the supporting arm 21 upwardly and causing interengagement of the corresponding set of contacts. The electromagnet 32 corresponding to the incoming line will be retained energized as long as the call exists. The electromagnet 28 corresponding to the actuated trunk bar, however, will be released immediately after the contact set has been actuated and will return to normal carrying with it all its contact actuating arms with the exception of the one engaged by the grooved cam 24 of the actuated line bar. Another bar, however, representing an idle trunk or outgoing line will be immediately rotated to set or receptive position. Upon the rotation of the next trunk bar to set position, the insulating portion 40 thereof will engage the forward face of the corresponding cam 24 of the actuated line bar and will be held from passing into operative relation to the corresponding contact set by means thereof, the shaft 7 turning freely in the yoke 20. Upon the termination of a connection, means will be actuated which will cause the deenergization of the electromagnet 32, and the corresponding bar 5 will then be rotated back to its normal position by its spring 31, thus releasing the contact actuating arm 21 which under the tension of the spring 23 will be rotated back to normal position in alignment with the other unactuated contact arms of the same rod.

As many modifications might readily be made in this invention without departing from the spirit thereof, the invention should be limited merely by the scope of the appended claims.

I claim:

1. In a telephone switch, sets of rotatable bars, contact springs adjacent and individual to said bars respectively, and means for rotating a bar of each set to effect interengagement of their respective contact springs. 105
2. In a telephone switch, sets of rotatable bars, contact sets adjacent to said bars, and means whereby the rotation of a bar of each set will actuate a contact set. 110
3. In a telephone switch, sets of rotatable bars, stationary contact sets adjacent to said bars, and means whereby the rotation of a bar of each set in a definite order only will actuate one of said contact sets. 115
4. In a telephone switch, sets of rotatable bars, the bars of one set being at an angle to those of the other, contact springs individual to each of said bars and in proximity to their adjacent points, and means for rotating a bar of each set to effect interengagement of their respective contact springs. 120
5. In a telephone switch, sets of rotatable bars, the bars of one set being at an angle to those of the other, contact springs adjacent and individual to said bars respectively, 125

and means whereby rotating a bar of each set in a definite order only will effect interengagement of their respective contact springs.

5 6. In a telephone switch, sets of rotatable bars, the bars of one set being adjacent and at substantially right-angles to those of the other, contact springs individual to each of said bars in proximity to their adjacent 10 points, and means for rotating a bar of each set to effect interengagement of their respective contact springs.

15 7. In a telephone switch, sets of rotatable bars, the bars of one set being at an angle to those of the other, contact springs individual to each of said bars in proximity to their adjacent 20 points, means whereby rotating a bar of each set will effect engagement of their respective contact springs, and electromagnetic means for rotating said bar.

25 8. In a telephone switch, sets of rotatable bars, the bars of one set being at an angle to those of the other, stationary contact sets adjacent to said bars, means whereby the rotation of a bar of each set will actuate one of said contact sets, and means depending upon the rotary position of a single one of said bars for maintaining said contact set actuated.

30 9. A telephone switch comprising sets of rotatable shafts, the shafts of one set being at an angle to those of the other, multiplied circuit terminals mounted adjacent to the shafts of said sets respectively, and means 35 whereby the selective and successive rotation of a shaft of each set in a definite order only will effect interengagement of the terminals of a predetermined circuit of each group.

40 10. A telephone switch comprising sets of rotatable shafts, the shafts of one set being at an angle to those of the other, multiplied circuit terminals mounted adjacent to the intersecting points of the shafts of said sets respectively, means whereby the selective and 45 successive rotation of a shaft of each set will effect interengagement of the terminals of a predetermined circuit of each group, and means depending upon the rotary position of a certain one only of said shafts for 50 maintaining the interengagement of said terminals.

55 11. In a telephone switch, sets of rotatable bars, the bars of one set being at an angle to those of the other, contact sets mounted independently of and in proximity to the adjacent points of said bars respectively, and means for successively rotating a bar of each set to actuate the contact set in proximity to their adjacent points.

60 12. In a telephone switch, sets of rotatable bars, sets of fixed spring contacts mounted with their free ends in proximity to intersecting points of said bars, coöperating contact actuating members mounted 65 on said bars at their points of intersection,

said contact actuating members being so arranged that the rotation of a bar of each set will actuate the contact set in proximity to the point of intersection of said bars.

13. In a telephone switch, sets of bars, the bars of one set being at an angle to those of the other, contact sets in proximity to the adjacent points of said bars, a flexible arm rotatably mounted on each of the bars of the first set adjacent to each of the bars of the second set, a cam on each of the bars of the second set in operative relation to its respective flexible arm, and separate means for displacing a bar of each set, whereby a flexible arm and a cam will coöperate to actuate the adjacent contact set.

14. In a telephone switch, sets of bars, the bars of one set being arranged at an angle to those of the other, a terminal bank, sets of contact springs projecting from said bank, the free ends of said springs being in proximity to the intersecting points of said bars, means for successively rotating a bar of each set whereby the contact set in proximity to their point of intersection will be actuated 90 and means depending on the rotary position of a single one of said bars for maintaining said contact set actuated.

15. In a switch, the combination of sets of intersecting shafts, relatively stationary contact sets mounted independently of said shafts at the intersections thereof, and means effective upon conjoint angular displacement of two intersecting shafts for operating a contact set.

16. In a switch, the combination of sets of intersecting bars, contact sets mounted independently of and adjacent the intersections of said bars, and means effective upon conjoint displacement of two intersecting 105 bars for operating the adjacent contact set.

17. In a switch, the combination of sets of intersecting bars, sets of spring contacts rigidly mounted in a frame, with their free ends adjacent the intersections of said bars, and means effective upon conjoint displacement of two intersecting bars for operating the adjacent contact set.

18. In a switch, the combination of sets of intersecting shafts, contact sets at the intersections of said shafts, means effective upon conjoint angular displacement of two intersecting shafts for operating a contact set, said means comprising a movable arm carried by one of said shafts and a projection 120 carried by the other.

19. In a switch, the combination of sets of intersecting bars, contact sets at the intersections of said bars, means for displacing any bar of one of said sets, a flexible arm carried 125 by said bar adjacent each bar of the other set, a rigid projection on each bar of the other set adjacent each bar of the first-mentioned set, and means for displacing any bar of said other set, the said flexible arm and 130

said rigid projection at the intersections of said displaced bars coöperating to actuate a contact set.

20. In a switch, the combination of sets of intersecting bars, contact sets at the intersections of said bars, means for displacing any bar of one of said sets, a flexible arm carried by said bar adjacent each bar of the other set, a rigid projection on each bar of the other set adjacent each bar of the first-mentioned set, means for displacing any bar of said other set, the said flexible arm and the

rigid projection at the intersections of said displaced bars coöperating to actuate a contact set, and a detent adapted to maintain 15 displaced said flexible arm during the continued displacement of the bar of the said other set.

In witness whereof, I hereunto subscribe my name this 7th day of May A. D., 1913.

JOHN N. REYNOLDS.
